UNITED STATES PATENT OFFICE.

JAMES HARMER KNIGHT, OF WESTTOWN, PENNSYLVANIA.

COIN-CARD.

No. 889,377.

Specification of Letters Patent.

Patented June 2, 1908.

Application filed June 10, 1907. Serial No. 378,876.

To all whom it may concern:

Be it known that I, JAMES HARMER KNIGHT, a citizen of the United States, and a resident of Westtown, Pennsylvania, have 5 invented certain new and useful Improvements in Coin-Cards, of which the following is a specification accompanied by drawings.

This invention relates to an improved form of card or holder for transmitting coins by 10 mail, and the objects of the invention are to simplify the construction of such a device, reduce the cost of manufacture and provide a device which is stiff, light and strong, and may be used repeatedly in sending coins back 15 and forth through the mail before its usefulness is destroyed.

Another object of the invention is to secure a card which will carry any fractional parts 20 of a dollar and according to this invention in the case of cash purchases by mail, any excess in payment may be replaced at once upon the card and returned to the sender.

Further objects of the invention will hereinafter appear and to these ends the invention 25 consists of a coin card having the features of construction and mode of operation substantially as hereinafter fully described and claimed in this specification and illustrated in the accompanying drawings, in 30 which,—

Figure 1 is a plan view of the card, and Fig. 2 is a transverse sectional view.

Referring to the drawings, A represents the coin card comprising a single sheet of thin 35 flexible material, preferably thin sheet metal, although any suitable material may be used. The card should preferably be of about the right size to insert in an ordinary envelop. The corners of the card are preferably cut 40 away or beveled at B to enable the card to be readily inserted in an envelop and prevent the envelop or other covering from being cut or torn as the card is inserted and in transmission through the mails.

45 The edges C of the card as shown are bent inwardly to form thickened margins, thereby materially stiffening the card and forming marginal flanges, cleats or pockets for holding and retaining one edge of the coins placed 50 around the margin of the card. The body of the card is punched or otherwise cut or prepared in such manner as to form apertures D, E, and F, into which project the ears or clips G formed out of the body of the card itself 55 and adapted to be bent backwardly over the uncovered edges of the coins which have been

slipped under the outer flange C of the card as indicated in dotted lines in Fig. 1. Preferably a series of apertures H is provided in the card around the margin to make the card 60 lighter and indicate the positions of the smaller coins.

The central portion of the card is also as shown provided with larger apertures I to indicate the positions of the larger coins, and 65 from these apertures ears or clips J radiate, integral with the body of the card and adapted to be bent backward over the coins placed over the apertures I as indicated in Fig. 1.

70 By removing portions of the sheet as D, E, F, H and I according to a suitable design the card is much reduced in weight while the remaining portions are so designed that they are readily utilized for securing coins of 75 different denominations to the face of the card.

The arrangement of perforations or apertures shown simplifies both the use and manufacture of the card. The marginal 80 holes indicate where to place the smaller coins, as dimes, pennies and nickels, while the quarter and half dollar are adapted to be placed over the larger central apertures.

According to my construction, coins may 85 be placed in the corners of the card at B, and the corresponding ears G are adapted to be bent over the coins. Along the margins, there are two ears G provided for each coin and for the larger coins at the center of the 90 card. There are four ears provided for each coin, although the number of ears may be varied as desired.

The number of marginal holes is preferably such that only the smaller and lighter 95 coins need to be used to make up any amount from one to ninety-nine cents, the latter amount being made up of nine dimes, one nickel and four pennies.

I claim and desire to obtain by Letters 100 Patent the following:—

1. A coin card comprising a piece of thin, flexible material having an inturned edge forming a marginal socket portion for holding the edges of coins, and inwardly extending adjustable ears or clips integral with the body of the coin card and coöperating with said socket portion to hold the coins.

105 2. A coin card comprising a single piece of thin, flexible material having an inturned edge forming a marginal socket portion for holding the edges of coins, and inwardly ex-

tending adjustable ears or clips integral with the body of the coin card and capable of being reversely bent over the coins to co-operate in holding them within the limits of the card.

3. A coin card comprising a single piece of thin, flexible metal having central apertures and integral ears or clips radiating outwardly from said apertures and adapted to be bent inwardly over the edges of coins placed over said apertures.

4. A coin card comprising a single piece of thin, flexible material having an inturned edge forming a flange under which the edges of coins may be placed, inwardly extending ears or clips integral with the body of the card and adapted to be reversely bent over the uncovered edges of said coins, central apertures and ears or clips integral with the body of the card and radiating outwardly

therefrom for holding coins in the middle portion of the card.

5. A coin card comprising a single sheet of thin, flexible metal having an inturned edge forming a marginal socket portion for holding the edges of coins, said metal sheet also having a marginal series of apertures adjacent the inturned edge and central apertures, adjustable ears or clips integral with the body of the sheet and extending inward from the marginal apertures, and similar ears or clips radiating outward from the central apertures. 25 30

In testimony whereof I have signed this specification in the presence of two subscribing witnesses. 35

JAMES HARMER KNIGHT.
